CLAIM

The ornamental design for a L-shaped platform bed with trundle and drawers, as shown and described.

DESCRIPTION

FIG. 1 is a front, right and top perspective view of a L-shaped platform bed with trundle and drawers, showing my design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 2.

1 Claim, 9 Drawing Sheets
